UNITED STATES PATENT OFFICE.

LEONARD BAILEY, OF HARTFORD, CONNECTICUT.

DESIGN FOR A HAND-WHEEL.

SPECIFICATION forming part of Design No. 13,621, dated February 20, 1883.

Application filed October 30, 1882. Term of patent 7 years.

To all whom it may concern:

Be it known that I, LEONARD BAILEY, of Hartford, in the county of Hartford and State of Connecticut, have invented and produced a new and original Design for a Hand-Wheel, of which the following is a specification, reference being had to the accompanying drawing, forming part thereof.

Heretofore hand-wheels have been made with the rim of a round form, having generally a plain finished surface, or being left in a rough state as they come from the molds in which they are cast.

The leading features of my design are the roughened side surfaces of the rim of the wheel, of reticular pattern, formed in the casting, and the smooth periphery which can be polished or plated to give a finished effect to the wheel. The center hub and spokes of the wheel may be of any customary curved or other pleasing form.

A represents the reticular sides of the rim.

This is intended to be the same on both sides of the wheel, and is formed in the molds in casting, so that the surface presents the usual effect of such surfaces, and is finished by cleaning and plating or with some suitable pigment.

B is the exterior surface of the rim forming the periphery of the wheel. This is somewhat projected or raised from the reticular sides, so as to form a band, and may be turned smooth and plated, so as to present a polished and finished surface extending all around the edge of the wheel.

What I claim as my invention is—

The design for a hand-wheel herein shown and described, wherein the sides of the rim are of a reticular pattern and the edge presents a smooth band.

LEONARD BAILEY.
